MACHINE FOR TESTING GOLF BALLS AND
THE LIKEWilbert W. Cranford and George I. Butler, La
Grange, Ill.

Application March 16, 1936, Serial No. 68,996

18 Claims. (Cl. 73—51)

Our invention consists of a machine for testing the resilience and elastic response of golf balls under conditions the same as those obtained in using such balls in play, as a result of which the relative playing value of such balls, for example, in driving, may be accurately determined in advance. Our invention includes an impact member having an impact surface for striking a ball or article being tested; means for moving said member from a potential position to said impact position and for repeatedly developing the same momentum at said impact position, for successive testing operations; a reaction member associated with a ball or article in testing position, and movable by reaction of a tested ball or article from impact of said impact member; loading means for opposing reactive movement of said reaction member; registering devices for indicating the reactive movement of said reaction member; operating mechanism for said registering devices, which is inactive during reactive movement of said reaction member, and which is operative during return movement of said reaction member to its position of rest; retracting mechanism for moving the impact member back from its impact position, after impact with a ball or article being tested, whereby upon impact with a ball or article being tested, the impact member may "follow through" with the same effect as in golf strokes properly applied, and be at once retracted to permit the reaction member to fully return to its position of rest adjacent to the next ball or article to be tested, when in its impact position; setting mechanism for moving the impact member to a potential position for movement when released, to its impact position, and also for moving the retracting mechanism to its set position out of the path of impact movement of the impact member; and retarding devices for the operating mechanism of the registering devices, insuring accurate operation of the registering devices and cushioned movement to its position of rest, of the reaction member. The impact member and the reaction member, as embodied in our machine described herein as illustrative of our invention, are in the form of gravity-actuated oscillatory arms, and while the operation of the machine is described in connection with testing golf balls, it will be understood that our invention is applicable to the testing of the resilience and elastic response of any articles susceptible of being compressed by impact and of quickly reacting to their original conformations.

55 Our invention will be best understood by refer-

ence to the accompanying drawings illustrating a preferred embodiment thereof, in which

Fig. 1 shows our machine in front elevation, with the dial thereof broken away to more clearly show parts of the construction, 5

Fig. 2 is a plan view of the machine shown in Fig. 1, with the dial shown in horizontal, sectional view,

Fig. 3 is a vertical, sectional view to an enlarged scale, of the structure shown in Fig. 2, taken along 10 the line 3—3,

Fig. 4 is a rear elevation to an enlarged scale, of the machine shown in Figs. 1 and 2,

Fig. 5 is a vertical, sectional view to an enlarged scale, of the structure shown in Fig. 2, 15 taken along the line 5—5,

Fig. 6 is a horizontal, sectional view to an enlarged scale, of a part of the structure shown in Fig. 1, taken along the line 6—6,

Fig. 7 shows in a view similar to Fig. 2 and to 20 an enlarged scale, the devices employed to release the mechanism for restoring the registering devices to their zero or initial position,

Fig. 8 shows in a view similar to Fig. 3, and to a much enlarged scale, parts of the pawls and 25 ratchet wheel constituting part of the mechanism for operating the registering devices.

Fig. 9 is a vertical, sectional view to an enlarged scale, of a part of the structure shown in Fig. 1, taken along the line 9—9, 30

Fig. 10 is a horizontal, sectional view to a further enlarged scale, of a part of the structure shown in Fig. 4, taken along the line 10—10, and

Fig. 11 is a vertical, sectional view to a further enlarged scale, of a part of the structure shown 35 in Fig. 2, taken along the line 11—11.

Similar numerals refer to similar parts throughout the several views.

As illustrated in Figs. 1 and 2, our testing machine consists of a base 10, which preferably is 40 of massive material, for example, iron or steel, supporting a vertical post 11 carrying the operating mechanism, and at its front portion, supporting a horizontal bar 12 carrying the registering mechanism of the machine. 45

The post 11 supports a plate 13 which in turn supports upper and lower bearing housings 14 and 15 respectively supporting the impact arm 16 and the reaction arm 17 for oscillatory movement. The housing 15 is not shown in Figs. 1 50 and 2, as it is concealed by other parts of the machine.

In Fig. 1, the reaction arm 17 is shown in its position of rest, said arm having secured to its lower end portion, a cage 18 for holding a ball 19, 55

or other article to be tested, in impact position, the upper end portion of said arm having secured thereto a weight 20 counterbalancing the lower portion of said arm and the parts carried thereby, 5 about its pivotal support. The impact arm 16 carries at its outer end, a weight 21 having an impact surface 21a for engaging the ball at nearly the end of its downward swing. The impact arm 16 is shown in Fig. 1, in its impact position, beyond which it moves to the left during an impact 10 swing, until a spring 22 carried by said arm engages a tripping screw 23 carried by a retracting lever 24 which then is in vertical or set position, to release said lever and permit it to function as 15 below described. In this manner, the impact surface 21a, after striking the ball 19, continues its movement through the impact position shown in Fig. 1, affording a reaction surface for the compressed face of the ball, in substantially the same 20 manner that the face of a playing club affords such a surface during the "follow through" of a stroke in actual play. The reaction of the ball is thus communicated to the cage 18 and to the reaction arm 17, and the amount of the reactive 25 movement of the arm 17 is a measure or indication of the amount of the reaction of the ball to the impact, and affords an indication of the "liveliness" of the ball. This quality of the ball depends upon two factors, first, its elasticity, that 30 is, how perfectly it will return to its original or normal shape after being compressed by impact, and second, its quickness of elastic response, that is, how quickly it will return to its normal shape. For obviously, in play, the flight of the ball depends 35 not only on its elasticity, but also on whether its reactive response elastically, is accomplished while still in contact with the impact surface of the playing club. By providing impact relations in our machine which are of the same kind as exist in actual play, we are able to 40 accurately measure and grade the playing value of the golf balls tested. Again, it is known, that differences in mass of the balls, affect their response in actual play. As a result of the impact relations referred to in our machine, such mass 45 differences produce corresponding reaction differences, which are factors in integrating the factors involved in reaction of the balls to impact, and the reactive movement of said reaction arm, is a correct indication of such integration.

In Fig. 1, the reaction arm is shown in its position of rest or its initial position, before it has reacted to the left from the impact communicated to the ball 19 by the impact arm 16. In so 50 reacting and swinging to the left, the reaction arm 17 carries the cage 18 with it, and the ball 19 which is then free, rolls on to and down a discharge runway 25 to a trough 26 out of the path of the reaction arm 17, for removal at the convenience of the operator. As below described, 55 the reaction arm 17, excepting for a predetermined load upon it, which is preferably constant to afford accurate and relative indications of the playing value of balls successively tested, is free from retarding forces and does no other work, to the end that the amount of its reactive swing will be an accurate indication of the playing 60 value of a tested ball, and to measure the amount of said reactive swing and indicate said playing value, we provide registering devices operated as 65 below described by return movement of the reaction arm to its position of rest. It is thus necessary that the reaction arm return positively to its position of rest to effect accurate operation of 70 the registering devices, and it is also important

that said return movement be damped to avoid injury to the parts that might result from a free swing of the reaction arm to its position of rest, and abruptly stopping said return swing by unyielding surfaces required for accuracy, to establish a fixed position for said position of rest, as well as to avoid any and all rebound of the reaction arm from its position of rest, since said rebound would give a false reading to the registering devices.

The "follow through" movement of the weight 21, causes the weight to move a little to the left (viewing Fig. 1) of the position occupied by the ball 19, before the tripping screw 23 is operated by the spring 22, in which position the impact arm 16 would prevent the reaction arm 17 from returning to its position of rest, by engaging the cage 18. The retracting lever 24, as will be shown, is pivotally supported at its lower end on the base 10, and as shown in Fig. 1, has extending to the right from its upper portion, a retracting arm 27 carrying at its right hand end, a cam arm 28 provided at its upper end with a cam 29 for engagement by an inclined plate 30 carried by the impact arm 16, when the latter is moved in the manner below described, to its set or potential position. Such engagement of the cam 29 by the plate 30, raises the retracting arm 27 and moves the retracting lever 24 to vertical position, in which position it is held until released, as will be described, by operation of the tripping screw 23, to permit the "follow through" movement of the impact arm 16. The operation of the tripping screw 23 at the end of said "follow through" movement, releases the retracting lever 35 24, and the weight of the arms 27 and 28 moves the retracting lever 24 to the right to the position shown in Fig. 1, during which movement a stud 31 carried by said lever, engages the impact arm 16 and retracts it from its "follow through" 40 position to substantially the position shown in Fig. 1. Since this retracting movement of the impact arm 16 occurs immediately at the end of the "follow through" movement of said impact arm, it occurs during the reactive swing of the 45 reaction arm 17, thereby removing all obstruction to the positive return of the reaction arm 17 to its position of rest.

To dampen the return movement of the reaction arm 17 to its position of rest, a dash pot 32 is supported on the base 10, with its piston connected with a bar 33 movable laterally on said base below the weight 21 and in the plane of movement of the reaction arm 17, which bar in its left hand position, extends into the path of return movement of the reaction arm 17 to its position of rest, and in its right hand position permits the reaction arm to solidly engage the left hand side surface of the base 10, thus establishing a definite and unchangeable terminal 60 position for return movement of the reaction arm 17, which is the position of rest for said reaction arm. The bar 33 has secured to it adjacent the cage 18, an angle bar 34, the upwardly extending leg of which is in the path of a pin 35 65 extending downwardly from the weight 21, said angle bar and said pin being so related laterally of the base 10, that during the "follow through" movement of the arm 16, and after the reaction arm 17 has begun its reactive swing from the impact on the ball 19, the pin 35 engages said angle bar and thereby moves the bar 33 to the left in readiness to cushion the return movement of the reaction arm 17. It will be noted that the reactive movement of the impact arm 16 above 70

described, moves the pin 35 to the right from engagement with the angle bar 34, freeing the bar 33 for cushioning or dampening movement controlled by the dash pot 32.

As shown in Figs. 1 and 2, the impact arm 16 is mounted on the front end of a shaft 36 mounted for oscillatory movement in the housing 14, and the rear end of said shaft has secured thereto a setting arm 37 in the path of a roller 38 pivotally mounted on the upper end of a setting member 39. As below described, the setting member 39 is connected by operating devices with a setting shaft 40 extending through and in front of the base 10, and having secured to its front end, a setting lever 41, so that when the lever 41 is depressed, the arm 37 is moved angularly to move the impact arm 16 away from its impact position, until a pin 16a, carried by the arm 16, as more clearly shown in Fig. 3, engages a notch 42a in a latch bar 42, holding the impact arm in its raised or potential position, indicated in dotted lines in Fig. 3, until said latch bar is moved from engagement with the pin 16a, to release the impact arm and permit it to swing downwards by gravity to acquire the desired momentum to be communicated by impact to a ball being tested. A stop plate 43 extends rearwardly from the plate 13, to limit return movement of the bar 39 when the setting lever 41 moves to its upper position after a setting operation.

As shown in Fig. 1, the upper end of the latch bar 42 is connected by a spring 44 with a bar 45 supported by the plate 13 and forming a guide for the latch bar, which spring tends to hold the latch bar in position to engage the pin 16a. The upper end of the latch bar 42 is engaged by the upper end of a bell-crank lever 46 pivotally supported at 47 by the bar 45 so that downward movement of the tripping rod 48 engaging the other end of the bell-crank lever, moves the latch bar 42 against the action of the spring 44, from its position of engagement with the pin 16a.

As shown in Fig. 1, the lower end of the rod 48 is connected with the outer end of a lever 49 pivotally supported at 50, the other end of said lever 49, as shown in Fig. 9, resting on the rear end of a second lever 51 pivotally supported on the end of the base 10 at 52 and projecting in front of the base to carry a knob 53 conveniently accessible to the operator of the machine. A stop 54 is provided to limit upward movement of the knob 53. As a result, when the impact arm 16 is in its set position, depressing the knob 53 moves the rod 48 downwardly, and this in turn moves the latch bar 42 from engagement with the pin 16a, and the impact arm 16 is free to begin its impact movement.

As shown in Figs. 1 and 2, the machine is provided with a supply runway 55 for delivering balls to be tested, to the impact position indicated in Fig. 1, the outer or forward end of said runway being conveniently accessible to the operator of the machine, and supported by an arm 56 extending from a column 57.

As shown in Fig. 1, the bar 12 has mounted on its ends, columns 57 and 58, to support a bar 59 in horizontal position and slightly below the axis of oscillation of the reaction arm 17, said bar 59 having mounted thereon an angle bar 60 to support as shown in Fig. 2, a bearing block 61 for supporting a pointer 62, and to also support an annular dial 63 cooperating with said pointer and coaxial with the support thereof. The block 61 is provided with a flange 61a at its front end,

secured to the angle bar 60, and supporting a spring 64 connected with said pointer to return the latter to its zero position against a resilient stop 65 carried by said angle bar, when said pointer is released after a registering movement. 5 The pointer 62 is carried by a tubular shaft 66 having its bearing support in the block 61, the axis of said tubular shaft being in line, or substantially so, with the axis of oscillation of the reaction arm 17, operating devices below described being provided between said reaction arm and said tubular shaft, to turn said tubular shaft and said pointer to an operated position by return movement of said reaction arm after its reaction swing, to its position of rest, said operating devices also serving to hold said pointer in its operated position, until the operating train of said operating devices is opened. 10 15

As shown in Fig. 1, a brake bar 67 is provided, to retard return movement of the reaction arm 17 to its position of rest, and this, together with the action of the dash pot 32, prevents rebound of the reaction arm 17 at the end of its said return movement.

As shown in Fig. 2, a releasing bar 68 is provided to open the operating train of the pointer 62 as below described, by each operation of the setting shaft 40, to move the impact arm 16 to its potential position, as follows: said bar 68 is mounted for reciprocating movement in supporting blocks 69 and 70 carried by the angle bar 60, and in the position shown does not affect the said operating train, opening of said train being effected by movement of said bar 68 to the left. The bar 68 is normally held in its right hand position by a spring 71 acting on a second bar 72 parallel with the bar 68 and reciprocable therewith through the blocks 69 and 70. A crank 73 is provided for moving the bars 68 and 72 to the left against the action of the spring 71, which 40 crank is formed on the upper end of a releasing rod 74 shown in Fig. 1 and mounted for oscillatory movement in the bars 12 and 59. The lower end portion of the rod 74 has secured thereto a crank 75 through the outer end of which a rod 45. 76 extends, the right hand end of said rod as indicated in Fig. 1, having connection with the shaft 40, so that for each setting movement of said shaft, the rod 76 is moved to the right and operates the crank 75 through a spring 77 disposed between the left hand end of the rod 76 and said crank, thereby moving the releasing bar 68 to the left and opening the operating train of the pointer 62. The spring 77 permits the releasing movement of the bar 68 to be less than 55 would otherwise be the case, and to be completed before the end of the setting movement of the shaft 40, which is an advantage in adjusting the releasing mechanism controlling the continuity of said operating train. 60

In Figs. 1 and 2 we also illustrate recording mechanism for making a record of each reactive movement of the arm 17 as follows: A plate 78 is supported in a plane substantially perpendicular to the axis of oscillation of the reaction arm 17, and adjacent the path of movement of the lower portion of said arm, by inverted U-shaped bars 79, 79 secured to said plate and to the dial 63. The lower portion of the plate 78 supports a horizontal shelf 80 extending rearwardly from 70 said plate, to support a roll 81 of paper tape which is held in place for rotary movement, by a vertical arbor 82 secured to said shelf and extending upwardly through said roll. The tape is drawn from the roll 81 as indicated at 81a, and across 75

- the front surface of the plate 78, the end of the tape being shown at 81b. The lower end portion of the reaction arm 17 is provided with a pencil or equivalent stylus 83, which is adjusted so that its marking point is substantially in the plane of the front surface of the plate 78. As a result, when a ball is tested, the reactive swing of the arm 17 moves the pencil 83 over the surface of the tape 81a in front of the plate 78, making a mark on said tape showing the height of said swing. The tape 81 is moved by the operator, across the plate 78 after each testing operation, sufficiently to present a fresh surface of the tape to the pencil 83 for the next testing operation, and the record or records thus made may by calculation or calibration, express in any desired system of units, the playing value of the ball or balls tested, and afford a permanent record of the testing of the same.
- 20 As shown in Figs. 1 and 2, the machine is preferably provided with a sub-base 10a, which may be of any suitable material, for example, wood or metal, to afford a substantial supporting surface.
- 25 In Fig. 3 the relation to each other of the impact arm 16, the reaction arm 17 and the retracting lever 24 and the parts carried thereby, is more clearly shown. In this figure the impact arm 16, the impact weight 21, the plate 30, and the locking pin 16a are shown in full lines in their positions at the instant of impact upon the ball 19 being tested, and the same parts are shown respectively in dotted lines for the set or potential position of the arm 16, at 16b, 21b, 30a and 16c; the reaction arm 17, the cage 18, and the counterweight 20 are shown in full lines for the initial or rest position of the arm 17, and the same parts are shown respectively in dotted lines for a reacted position of the arm 17, at 17a, 18a, and 20a; the retracting lever 24, retracting arm 27, cam arm 28 and cam 29 are shown in full lines for the position assumed by the arm 24 after its release to retract the impact arm 16 after a "follow through" movement, back to substantially its impact position, and said retracting lever and parts carried thereby are shown respectively in dotted lines for the set position of the lever 24, at 24a, 27a, 28a and 29a.
- 30 As shown in Fig. 3, the lever 24 is pivotally supported at its lower end at 84, on a stud 85 projecting upwardly from the base 10. The screw 23 is carried by a bell-crank lever 86 pivotally connected with the lever 24 at 87, said bell-crank lever being pivotally connected with the lower end of a releasing rod 88 extending upwardly adjacent the lever 24 through a guide bracket 89 carried thereby and terminating at its upper end just below the upper end of the lever 24 as shown in Fig. 11. As shown in the latter figure, the upper end of the rod 88 is loosely contained in a slot 24b in the edge of the upper end portion of the lever 24, and the upper end of said lever is mounted for lateral movement in a slot 90a in a bar 90 supporting a light-tension flat spring 91 above said slot 90a, so that for the set position of the lever 24 shown in dotted lines at 24a, a pin 92 carried by and extending above the upper end of the lever 24, engages the left hand end of said spring 91, holding the lever in its set position until the spring 91 is raised to disengage it from the pin 92. When the screw 23 is engaged by the spring 22 at the end of the "follow through" movement of the impact arm 16, the rod 88 is raised by operation of the bell-crank lever 86, thereby raising the spring 91 and effecting dis-
- 5 engagement of said spring from the pin 92, and permitting the weight of the retracting arm 27 and of the cam arm 28, to move the lever 24 to its position retracting the impact arm 16 to substantially its impact position. Retracting movement of the arm 27 is limited by engagement with a stop block 93 carried by a vertical bar 94 adjacent the arm 27 and constituting a part of the frame of the machine. As shown in Fig. 3, the bar 90 is supported on the lower ends of vertical bars 95, 95 extending downwardly from the plate 13.
- 10 As shown in Fig. 3, the reaction arm 17 has extending therefrom above its axis of oscillation, an arm 96 to which three pawls 97, 97a and 97b are pivotally connected at 98, which pawls engage a ratchet wheel 99 secured to a combined drum 100 and internal gear 101 mounted on a rotary shaft 102 substantially coaxially with the axis of oscillation of the reaction arm 17. The shaft 102 rotates in the tubular shaft 66 carrying the pointer 62 at its front end, the rear end of said tubular shaft having secured to it within the internal gear 101, a pinion 103 connected by an idler gear 104 rotatable on a fixed stud 105, with the internal gear 101.
- 15 As shown in Fig. 3, the brake bar 67 is pivotally supported at 106 on a block 107 carried by the angle bar 60, and from the block 107 an arm 108 extends to support a tensioning rod 109 extending at its lower end around the bar 67 and extending at its upper end to receive an adjusting nut 110 to change as desired, the pressure of the spring 111 between the arm 108 and the nut 110 and around the rod 109, to exert a desired upward pressure on the brake bar 67. Said brake bar 35 extends under the drum 100, and has secured to it a brake block 67a of suitable material, for example, leather, pressed upwardly against the drum by the upward pressure exerted on the brake bar 67 by the spring 111.
- 20 As shown in Fig. 3, the pencil 83 is held on the reaction arm 17 by a clamping plate 112, by suitable screws as indicated, to afford convenient adjustment of said pencil.
- 25 As shown in Fig. 3, the plate 78 is provided with horizontal guide bars 113 at the upper and lower edges of the record tape 81a, to prevent vertical displacement of said tape from its recording position. The plate 78 also carries flat spring clips 114 near the discharge end 81b of the tape, and a flat spring 115 to hold the tape 81a in flat condition on the plate 78, to be marked by the pencil 83. The plate 78 also supports a thin flat spring 116 under the tape 81a and in the path of movement of the pencil 83, to hold the tape 81a 55 slightly away from the plate 78 at the recording position of the tape, and to afford a resilient surface for engagement by the point of the pencil 83, to avoid undue marking friction, and to avoid the necessity for exact adjustment of the pencil.
- 30 As shown in Fig. 3, the dash pot 32 is provided through its outer end, with an adjusting screw 117 having a tapered longitudinal side groove 117a, to provide a desired degree of retardation of movement of the bar 33 to the right, when acted upon by the reaction arm 17 in returning to its position of rest in engagement with the base 10. A lock-nut 118 is mounted on the screw 117 to hold it in any adjusted position.
- 35 As shown in Fig. 4, the setting shaft 40 is provided at its rear end, with a crank 40a carrying a ball bearing 119 in a slot 120 in a plate 121 secured to the lower end portion of a bar 122 secured at its upper portion to the right hand edge of a plate 123, to the left hand edge of 75

which plate, the lower portion of the bar 39 is secured. The plate 123 is supported for oscillatory movement on a pivot 124, which, as more clearly shown in Fig. 5, is supported on the rear end of a stud 125 secured to and extending rearwardly from the post 11. The crank 40a is substantially vertical for the position of rest of the setting lever 41 (Figs. 2 and 6), for which position, and with the impact arm 16 in its retracted position, the setting arm 37 is in substantially the position and in the relation to the roller 38, shown in Fig. 4. As a result, and due to the shape indicated of the outer end portion of the arm 37, equal increments of setting movement of the lever 41, produce progressively smaller amounts of angular movement of the impact arm 16, thereby compensating for the increasing moment required to raise the weight 21. Thus a substantially uniform pressure is required downwardly on the lever 41 during a setting operation, the angular movement of the impact arm 16 being relatively rapid during the first part of a setting movement, and then decreasing in rapidity as the required lifting moment increases. As shown in Fig. 4, the rear end portion of the shaft 40 is supported by a bearing plate 126 secured to the post 11, and as shown in Fig. 10, a spring 127 is mounted on the shaft 40 between the plate 126 and the base 10, one end of which spring is secured to said shaft at 127a, the other end of said spring engaging the plate 126, to move the setting mechanism to its position of rest when the lever 41 is released, which movement is limited by the stop plate 43, in a position permitting free movement of the arm 37 relatively to the roller 38, during impact movement of the impact arm 16.

As shown in Figs. 4 and 10, the shaft 40 has secured thereto back of the plate 126, a collar 128 which together with the enlarged front end portion of said shaft, prevents longitudinal movement of the shaft in its bearings.

As shown in Fig. 4, the base 10 supports a bar 129 extending to the left from said base, to which bar the lower end of the bar 94 is secured. The bar 129 also carries a pivotal support 130 for the lower end of the latch bar 42, and has extending downwardly from its outer end portion, a stud 131 supporting the pivot 50 of the tripping lever 49.

As shown in Fig. 5, the housing 14 supports at its ends, ball-bearings 132 which in turn support the shaft 36 for free oscillatory movement. The housing 15 similarly supports ball-bearings 133 for the shaft 134, to the front end of which the reaction arm 17 is secured by means of a hub 135. The rear end of the shaft 134 has secured thereto a drum 136 having a circumferential groove 136a in which a thin, flexible metal tape 137 is disposed, one end of said tape being secured to said drum, and the other end of said tape, as more clearly shown in Fig. 4, extending down and being secured to a hollow weight 138, so that said weight will be raised by reactive movement of the reaction arm 17. The tape 137 is adjusted so that for the position of rest of the reaction arm 17, the weight 138 will be suspended by the tape, out of contact with other parts of the machine. The shell of the weight 138 is preferably light enough so that its requisite total weight is determined by the number of metal balls 138a contained in it, an aperture 138b being formed through the upper portion of the shell to facilitate inserting and removing the balls as desired.

The total amount of weight on the tape 137 is

preferably of an amount determined by the amount of momentum developed by impact movement of the impact arm 16, and the reactive ability of the balls, or other articles tested, to the end that the maximum reactive movement of the reaction arm 17 will effect operation of the registering pointer 62, well within its limit of movement and within the registering range of the dial 53.

As shown in Figs. 4 and 5, the housings 14 and 15 are supported in horizontal, parallel relation, one above the other, by a plate 139 secured to said housings and also to a block 140, which block is secured to the upper end of the post 11.

In Fig. 5, the support of the tubular shaft 66 by the bearing block 61 is shown, said shaft being freely rotary in said block, and the shaft 102 supporting the brake drum 100, being supported by and freely rotary in the tubular shaft 66. The shaft 102 has secured to its front end, a collar 102a to prevent longitudinal movement of said shaft in the tubular shaft 66, and the block 61 is mounted on the bar 59, with the axis of the shaft 102 substantially in alignment with the axis of the shaft 134. The block 61 is provided with a rear flange 61b supporting the bearing stud 105 for the idler gear 104, as indicated, and the manner of supporting the screw 31 by means of a stud 141 extending from and carried by the retracting lever 24, is also shown. The pawls 97, 97a and 97b are broken away in Fig. 5 to more clearly show the parts cooperating therewith.

In Fig. 7 the releasing mechanism for the pointer 62, is shown in plan view to an enlarged scale. The rods 68 and 72 are secured together by clamping blocks 142 and 143, the crank 73 by its operation above described, engaging the block 142 and moving said rods to the left in the supporting blocks 69 and 70, against the action of the spring 71. The block 143 by engaging the supporting block 69, limits movement of the rods 68 and 72 to the right by the spring 71 when the crank 73 is turned to the right to release said rods from operating pressure. A stop block 144 secured to the angle bar 60 in the path of the block 143, limits releasing movement of said rods by the operation of the crank 73. The right hand end portion of the rod 68 is bent laterally at 68a to extend under the pawls 97, 97a and 97b, and at its right hand end as shown in Fig. 8, said rod is provided with an upwardly bent end 68b in notches therefor in the pawls, so that releasing movement of the rod 68 as described, will move said pawls to the left and from engagement with the ratchet wheel 99. The pawls are shown in Fig. 8 in the position they occupy when the reaction arm 17 is in its position of rest, for which position, with the rod 68 in its right hand position, the end portions 68a and 68b of said rod 60 are not in engagement with but are closely adjacent to the edges of said pawls.

As shown in Fig. 7, the rods 68 and 72 have secured to them adjacent the supporting block 70, an angle plate 145, to the upwardly extending flange of which, a bell-crank lever 146 is pivotally secured at 147, said lever 146 having adjusting screws 148 and 149 engaging the plate 145. As shown in Fig. 3, the upper end of the lever 146 engages a notch in the upper end of a lever 150 pivotally mounted at 151 on a stud 152 supported by and extending rearwardly from the angle bar 60. The lever 150 is supported vertically in the plane of the brake bar 67, and as shown in Fig. 4, said lever is continued below its pivotal support 75

151 and formed at its lower end into a cam 150a engaging the upper surface of said brake bar. As a result, when the rods 68 and 72 are moved during a releasing operation, the lever 150 is 5 rocked on its pivotal support 151 and its lower cam end 150a depresses the brake bar 67. When the reaction arm 17 is returned to its position of rest by the action of the weight 138, the pawls 97, 97a and 97b drive the ratchet wheel 99 against 10 the frictional resistance of the brake block 67a pressing against the drum 100, which in turn through the gearing described, moves the pointer 62 to register on the dial 63, the amount of the displacement of the reaction arm 17. The adjustment of the brake spring 111 is such as to insure such deliberate return of the reaction arm 17 to its position of rest, that there is no possibility of "overthrow" of the registering devices, and in cooperation with the action of the dash 15 pot 32, no rebound from the base 18 when its rest position is reached, thus insuring accurate operation of the registering devices, yet insuring positive return to said rest position because of the dominance of the weight 138. The resulting position assumed by the pointer 62 is maintained by the pawls 97, 97a and 97b and by the engagement of the brake block 67a with the drum 100, until the next movement of the impact arm 16 to its set or potential position by depression of the lever 20 41, which, as above described, moves said pawls from engagement with the ratchet wheel 99, thus freeing said ratchet wheel and the gearing connecting the same with the pointer 62, for operation by the spring 64 to move the pointer 62 back 25 30 to its zero position. However, in view of the pressure of the brake block 67a being adjusted to oppose a considerable portion of the effect of the weight 138, and in view of it being desirable that the spring 64 shall be no stronger than required 35 40 to positively overcome the friction of the driving gearing connected with said pointer, the spring 64 is not able to overcome the brake friction adapted to partially oppose the action of the weight 138. To take care of this condition, at 45 the same time that the pawls 97, 97a and 97b are disengaged from the ratchet wheel 99, the cam 150a on the lever 150 depresses the brake bar 67 sufficiently so that the decreased pressure of the brake block 67a on the drum 100, permits 50 the spring 64 to move the pointer 62 back to its zero position against the spring stop 65, and slowly enough so that it will come to rest against said spring stop, and so be in a position to accurately register the next operation of the reaction arm 17. The adjusting screws 148 and 55 149 afford a means for accurately adjusting the lever 150 through the bell-crank lever 146, to secure the requisite decrease of pressure of the block 67a against the drum 100 to secure the results described.

their combined thickness is substantially less than the face of the ratchet wheel 99, insuring the proper engagement at all times of any one of the pawl teeth with the teeth of the ratchet wheel, as occasion may require.

The dial 63 may be graduated in any desired manner, so that it will either by calculation or calibration, indicate the reactive response of the article tested in any desired units.

The cycle of operation of our machine is as follows. Beginning with the reaction arm 17 in its initial position, the pointer 62 in its last actuated position, and the impact arm 16 in its retracted position, which positions result from the last testing operation, the setting lever 41 is first depressed which releases the pointer 62 for return to its initial position and at the same time disengages the pawls 97, 97a, 97b from the ratchet wheel 99, further setting movement moving the impact arm 16 to its raised position engaging the latch bar 42, at the same time moving the retractor lever 24 to its set position; a ball 19 to be tested is then placed on the descending runway 55 and rolls to impact position in the ball cage 18 on the arm 17; the tripping lever 51 is then depressed which releases the impact arm 16, the weight 21 carried thereby strikes the ball and the "follow through" of the weight permitted by the set position of the retractor 24, backs up the ball so that its resilience imparts a corresponding blow or operating force to the reaction arm 17, moving it upward and raising the weight 138 until the force of the impact is spent, at the same time moving the pawls 97, 97a, 97b freely over the teeth of the ratchet wheel 99; during the "follow through" of the impact arm 16, said arm moves the bar 33 into the return path of the arm 17, thereby moving the piston in the dashpot 32 to its operative position, and at the same time the arm 16 releases the retractor lever 24 which in turn moves the arm 16 and the weight 21 back from impact position and out of the path of return movement of the arm 17; during said "follow through" movement and the beginning of upward movement of the arm 17, the ball 19 is delivered to the upper end of the discharge runway 25, down which it rolls out of the path of return movement of the arm 17, while the latter is moving upward; when the arm 17 reaches its uppermost position, the weight 138 moves said arm towards its initial position, checked somewhat by the brake bar 67 and brake block 67a, which return movement of the arm 17, by engagement of the pawls 97, 97a, 97b with the ratchet wheel 99, moves the pointer 62 over the dial to its indicating position, the movement of the pointer being proportional to the return movement of the arm 17, which latter of course equals the impact movement of said arm, as a result of which the pointer movement affords an accurate indication of the amount of the blow or impact imparted by the ball to the impact arm 17, which in turn is an indication of the degree of resilience of the ball tested; during the final part of the return movement of the arm 17, it engages the bar 33, so that the return movement of said arm just before it reaches its initial position, moves the piston in the dash pot 32, checking the movement of said arm and insuring that it come to rest in its initial position without rebound, to afford corresponding inaccuracy in the indication afforded by the pointer 62; when the arm 17 reaches its initial position, the machine is in readiness for its next cycle of operation.

Our testing machine above described, thus 75

affords a means for accurately indicating and recording the reactive response of articles tested, either relatively to each other if no particular system of units is employed, or relatively to a 5 standard test article, if the same be used as a basis of comparison, or in any desired system of units, depending upon the calibration or construction of the dial and recording mechanism.

While we have shown our invention in the 10 particular embodiment above described, it will be understood that we do not limit ourselves to those particular constructions, as we may employ equivalents thereof known to the art without departing from the scope of the appended claims.

15 What we claim is:

1. In a machine for testing golf balls and the like, the combination of an oscillatory impact arm carrying an impact surface, an oscillatory reaction arm, a ball cage carried by said reaction arm 20 in the path of said impact surface, said ball cage exposing a surface of a ball being tested to the impact of said impact surface, means for producing substantially uniform impacts of said impact surface upon balls successively tested, registering 25 devices showing the amount of reaction of said reaction arm to the impact upon a tested ball, and operating mechanism between said reaction arm and said registering devices, said operating mechanism being inactive for reactive 30 movement of said reaction arm and operated by return movement of said reaction arm to its impact receiving position.

2. In a machine for testing golf balls and the like, the combination of an oscillatory impact 35 arm carrying an impact surface, an oscillatory reaction arm, a ball cage carried by said reaction arm in the path of said impact surface, said ball cage exposing a surface of a ball being tested to the impact of said impact surface, means for producing substantially uniform impacts of said impact 40 surface upon balls successively tested, registering devices showing the amount of reaction of said reaction arm to the impact upon a tested ball, setting mechanism for moving said impact arm to a potential position, and restoring 45 mechanism for said registering devices and activated by said setting mechanism.

3. In a machine for testing golf balls and the like, the combination of an oscillatory impact arm carrying an impact surface, an oscillatory reaction arm, a ball cage carried by said reaction arm 50 in the path of said impact surface, said ball cage exposing a surface of a ball being tested to the impact of said impact surface, means for producing substantially uniform impacts of said impact 55 surface upon balls successively tested, registering devices showing the amount of reaction of said reaction arm to the impact upon a tested ball, operating mechanism between said reaction arm and 60 said registering devices, said operating mechanism being inactive for reactive movement of said reaction arm and operated by return movement of said reaction arm to its impact receiving position, setting mechanism for moving said impact arm to a potential position, and restoring 65 mechanism for said registering devices and activated by said setting mechanism.

4. In a machine for testing golf balls and the like, the combination of an oscillatory impact arm 70 carrying an impact surface, an oscillatory reaction arm, a ball cage carried by said reaction arm in the path of said impact surface, said ball cage exposing a surface of a ball being tested to the impact of said impact surface, means for producing substantially uniform impacts of said im- 75

pact surface upon balls successively tested, registering devices showing the amount of reaction of said reaction arm to the impact upon a tested ball, operating mechanism between said reaction arm and said registering devices, said operating 5 mechanism being inactive for reactive movement of said reaction arm and operated by return movement of said reaction arm to its impact receiving position, and retarding devices associated with said operating mechanism and retarding 10 said return movement of said reaction arm.

5. In a machine for testing golf balls and the like, the combination of an oscillatory impact arm carrying an impact surface, an oscillatory reaction arm, a ball cage carried by said reaction arm 15 in the path of said impact surface, said ball cage exposing a surface of a ball being tested to the impact of said impact surface, means for producing substantially uniform impacts of said impact surface upon balls successively tested, 20 registering devices showing the amount of reaction of said reaction arm to the impact upon a tested ball, and retracting mechanism associated with said impact arm and released thereby at the end of the impact movement thereof, operation 25 of said retracting mechanism moving said impact arm back from its impact position.

6. In a machine for testing golf balls and the like, the combination of an oscillatory impact arm carrying an impact surface, an oscillatory reaction arm, a ball cage carried by said reaction arm 30 in the path of said impact surface, said ball cage exposing a surface of a ball being tested to the impact of said impact surface, means for producing substantially uniform impacts of said impact 35 surface upon balls successively tested, registering devices showing the amount of reaction of said reaction arm to the impact upon a tested ball, retracting mechanism associated with said impact arm and released thereby at the end of the 40 impact movement thereof, operation of said retracting mechanism moving said impact arm back from its impact position, and setting mechanism for moving said impact arm to a potential 45 position and for moving said retracting mechanism to its set position out of the path of impact movement of said impact arm.

7. In a machine for testing golf balls and the like, the combination of an oscillatory impact arm carrying an impact surface, an oscillatory reaction 50 arm, a ball cage carried by said reaction arm in the path of said impact surface, said ball cage exposing a surface of a ball being tested to the impact of said impact surface, means for producing substantially uniform impacts of said impact 55 surface upon balls successively tested, registering devices showing the amount of reaction of said reaction arm to the impact upon a tested ball, and loading means opposing reactive movement of said reaction arm and tending to 60 hold the latter in its impact receiving position.

8. In a machine for testing golf balls and the like, the combination of an oscillatory impact arm carrying an impact surface, an oscillatory reaction arm, a ball cage carried by said reaction arm 65 in the path of said impact surface, said ball cage exposing a surface of the ball being tested to the impact of said impact surface, means for producing substantially uniform impacts of said impact surface upon balls successively tested, 70 registering devices showing the amount of reaction of said reaction arm to the impact upon a tested ball, and loading means opposing reactive movement of said reaction arm and tending to hold the latter in its impact receiving position, 75

the opposing force of said loading means being uniform throughout the reactive movement of said reaction arm.

9. In a machine for testing golf balls and the like, the combination of an oscillatory impact arm carrying an impact surface, an oscillatory reaction arm, a ball cage carried by said reaction arm in the path of said impact surface, said ball cage exposing a surface of a ball being tested to the impact of said impact surface, means for producing substantially uniform impacts of said impact surface upon balls successively tested, registering devices showing the amount of reaction of said reaction arm to the impact upon a tested ball, and loading means opposing reactive movement of said reaction arm and tending to hold the latter in its impact receiving position, said loading means comprising a drum operated by said reaction arm, and a weight suspended from said drum.

20 1. In a machine for testing elastic articles, the
combination of an impact member movable from
a set position to an impact position and having
an impact surface, means for developing uni-
25 form momentum of said impact member at its
impact position for successive testing operations,
means for holding an article to be tested with its
surface at said impact position, a reaction mem-
ber having a position of rest adjacent said article
30 with said article between said reaction member
and said impact position, said reaction member
being movable from said position of rest to an
impact-operated position, and loading means op-
posing reactive movement of said reaction mem-
35 ber and tending to hold the latter in its position
of rest.

11. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction member having a position of rest adjacent said article with said article between said reaction member and said impact position, said reaction member being movable from said position of rest to an impact-operated position, loading means opposing reactive movement of said reaction member and tending to hold the latter in its position of rest, and registering devices showing the amount of reactive movement of said reaction member.

12. In a machine for testing elastic articles,
55 the combination of an impact member movable
from a set position to an impact position and
having an impact surface, means for developing
uniform momentum of said impact member at its
impact position for successive testing operations,
60 means for holding an article to be tested with its
surface at said impact position, a reaction mem-
ber having a position of rest adjacent said article
with said article between said reaction member
and said impact position, said reaction member
65 being movable from said position of rest to an
impact-operated position, loading means oppos-
ing reactive movement of said reaction member
and tending to hold the latter in its position of
rest, registering devices showing the amount of
70 reactive movement of said reaction member, and
operating mechanism between said reaction mem-
ber and said registering devices, said operating
mechanism being inactive for reactive move-
75 ment of said reaction member and operated by

movement of said reaction member to its position of rest.

13. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction member having a position of rest adjacent said article with said article between said reaction member and said impact position, said reaction member being movable from said position of rest to an impact-operated position, loading means opposing reactive movement of said reaction member and tending to hold the latter in its position of rest, registering devices showing the amount of reactive movement of said reaction member, setting mechanism for moving said impact member to its set position, and restoring mechanism for said registering devices and activated by said setting mechanism. 5 10 15 20

14. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction member having a position of rest adjacent said article with said article between said reaction member and said impact position, said reaction member being movable from said position of rest to an impact-operated position, loading means opposing reactive movement of said reaction member and tending to hold the latter in its position of rest, registering devices showing the amount of reactive movement of said reaction member, operating mechanism between said reaction member and said registering devices, said operating mechanism being inactive for reactive movement of said reaction member and operated by movement of said reaction member to its position of rest, and retarding devices associated with said operating mechanism and retarding movement of said reaction member to its position of rest. 25 30 35 40 45

15. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction member having a position of rest adjacent said article with said article between said reaction member and said impact position, said reaction member being movable from said position of rest to an impact-operated position, loading means opposing reactive movement of said reaction member and tending to hold the latter in its position of rest, registering devices showing the amount of reactive movement of said reaction member, and retracting mechanism associated with said impact member and released thereby at the end of the impact movement thereof, operation of said retracting mechanism moving said impact member away from its impact position.

16. In a machine for testing elastic articles, the combination of an impact member movable from a set position to an impact position and having an impact surface, means for developing uniform momentum of said impact member at its impact 75

position for successive testing operations, means for holding an article to be tested with its surface at said impact position, a reaction member having a position of rest adjacent said article with said article between said reaction member and said impact position, said reaction member being movable from said position of rest to an impact-operated position, loading means opposing reactive movement of said reaction member and tending to hold the latter in its position of rest, registering devices showing the amount of reactive movement of said reaction member, retracting mechanism associated with said impact member and released thereby at the end of the impact movement thereof, operation of said retracting mechanism moving said impact member away from its impact position, setting mechanism for moving said impact member to its set position and for moving said retracting mechanism to its set position, and restoring mechanism for said registering devices and activated by said setting mechanism.

17. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction mem-

ber having a position of rest adjacent said article with said article between said reaction member and said impact position, said reaction member being movable from said position of rest to an impact-operated position, and loading means opposing reactive movement of said reaction member and tending to hold the latter in its position of rest, the opposing force of said loading means being uniform throughout the reactive movement of said reaction member. 10

18. In a machine for testing elastic articles, the combination of an impact member movable from a set position to an impact position and having an impact surface, means for developing uniform momentum of said impact member at its impact position for successive testing operations, means for holding an article to be tested with its surface at said impact position, a reaction member having a position of rest adjacent said article with said article between said reaction member and said impact position, said reaction member being movable from said position of rest to an impact-operated position, and loading means opposing reactive movement of said reaction member and tending to hold the latter in its position of rest, said loading means comprising a drum operated by said reaction member, and a weight suspended from said drum. 20 25
